UNITED STATES PATENT OFFICE.

EDWARD WESTON, OF NEWARK, NEW JERSEY.

DESIGN FOR A CASE FOR ELECTRICAL INSTRUMENTS.

SPECIFICATION forming part of Design No. 23,141, dated March 20, 1894.

Application filed February 21, 1894. Serial No. 501,052. Term of patent 14 years.

To all whom it may concern:

Be it known that I, EDWARD WESTON, of Newark, Essex county, New Jersey, have invented a new and original Design for Electrical Instrument Cases, of which the following is a specification.

In the accompanying drawing an instrument case exhibiting my design is shown in perspective. The conformation of said case is as follows: The general outline is triangu-

lar. The side A is flat. The edges B and C are convex. The edge E is concave at a, convex at b and straight at c.

I claim—

The design for an electrical instrument case substantially as herein shown and described.

EDWARD WESTON.
